DIRECTIONAL ANTENNA CONTROL

Joseph C. Lotter and Victor W. Lotter,
Seymour, Wis.

Application December 9, 1939, Serial No. 308,478

9 Claims. (Cl. 250—33)

This invention relates generally to the class of radiant energy and pertains particularly to improvements in beam radio antennae as used for transmission and reception of radio signals.

5 In the transmission and reception of radio signals, use is frequently made of antenna structures which are mounted to be rotated in a horizontal plane for the purpose of disposing the metal units of the structure from which the electric waves are sent out or upon which such waves are picked up, in the most advantageous position for receiving the waves or for sending them into the air in a desired direction. At the present time various means are employed for turning or 10 rotating such antennae, as by the use of electric motors or hand-controlled gear trains, but in all such structures the control means for turning the antenna must be placed in relatively close proximity to the base of the mast on which the antenna is supported, with the result that such mechanism is more or less exposed to the elements and in addition, the area surrounding the base of the mast has electric wires or mechanical elements extended therethrough for the control 15 of the mechanism, with the result that such area is made unsightly by wires or other apparatus as well as dangerous where electric current carrying wires must be employed.

20 The present invention has for its primary object to provide a new, novel and practical method for supporting a radio beam antenna so that it may be readily turned to any desired position and for effecting such turning in a novel manner from a remote point without the necessity of employing control apparatus around the outside of the mast or the base structure upon which such mast is supported.

25 Another object of the invention is to provide a novel mast supporting means whereby such mast may be rotated through a complete circle by the employment of hydraulic power, thus eliminating the use of gears or electrically driven motors at the base of or in the vicinity of the mast.

30 A further and more specific object of the invention is to provide a novel mast supporting means comprising a vertically disposed cylinder into which such mast extends with a piston unit in the cylinder beneath the mast and adapted to be shifted through the introduction of fluid there- 35 beneath and into the cylinder, the cylinder being operatively coupled with the mast in such manner that upon longitudinal shifting of the mast therein, rotary motion will be given to the same on its long axis so as to effect the turning of the 40 antenna structure supported upon its upper end.

A still further object of the invention is to provide in association with a structure of the above described character, a novel means for forcing the propelling fluid into the mast enclosed cylinder and a novel indicator means associated with the fluid impelling means whereby upon actuation of said last means, the operator will be able to determine the exact position to which the mast supported antenna is turned.

45 The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

20 In the drawing:

Fig. 1 is a view illustrating the apparatus embodying the present invention, parts of the same being in section and parts thereof in elevation and showing a radio beam antenna in side elevation and supported upon the mast.

25 Fig. 2 is a section on the line 2—2 of Fig. 1.

Fig. 3 is a view in plan of the antenna position indicator.

30 Referring now more particularly to the drawing, it will be seen that the mechanism embodying the present invention consists of two main units, one of which is indicated generally by the numeral 1 and may be referred to generally as the rotator while the other unit is indicated generally by the numeral 2 and may be referred to generally as the control unit.

35 The rotator unit 1 is designed to be mounted in any suitable location outside of the station where radio signals are received or from which such signals are broadcast and this unit may be mounted upon a tower, a building or directly upon the ground, if desired. The control unit is located within such building in a position which is convenient for the operator of the broadcasting or receiving apparatus and is operatively coupled in the manner hereinafter described with the rotator unit so that the control of the latter unit may be readily accomplished.

40 The unit 1 consists of a vertically disposed cylinder 3 which at its lower end may be secured in a suitable base 4 having a fluid passage 5 leading therethrough and into the lower part of the cylinder. Slidably disposed within the cylinder which is, of course, vertically arranged and

secured to any suitable support by means of attaching ears 6 or in any other suitable manner, is a mast 7 which projects a substantial distance above the upper end of the cylinder and has secured about it and above the upper end of the cylinder 3, the depending skirt 8 which slides over and encloses the upper end of the cylinder 3 in the manner shown to form a weather seal or cap which prevents rain, snow and dirt from working down into the cylinder between the same and the mast.

The mast supports upon its upper end the rotary beam antenna which is generally indicated by the numeral 9 and which is also conventionally shown in side elevation. No detailed showing has been made of this structure since it forms in itself no part of the present invention but may be of any standard design.

Secured in and extending through the wall of the cylinder 3 preferably at diametrically opposite points, are guide pins 10 which have their inner ends pointed as indicated at 11, and these pointed or cone-like ends of the guide pins engage in the spiral grooves 12 which are formed in and around the mast 7 so that when the mast is given longitudinal movement in the cylinder, the engagement of these pins in the spiral grooves will cause the mast to turn about its long axis.

Fitting snugly within the cylinder beneath the mast 7 is a piston unit consisting of a plate 13 to the under side of which is secured a piston cup 14, and interposed between the plate 13 and the bottom or lower end of the mast is an anti-friction unit indicated generally by the numeral 15. This latter unit acts as a thrust bearing between the piston unit and the mast, thus permitting fluid pressure to be applied to the piston unit so as to move it longitudinally in the cylinder while at the same time permitting the smooth and free turning of the mast on the piston unit.

The control unit 2 consists of a suitable housing or box 16 which is here shown as having one side removed so that the interior parts may be readily pointed out. Within this box is a fluid cylinder 17 within which is a piston head 18 carrying a cup washer 19 and attached to the piston head is a tubular stem 20. The outer end of the stem 20 carries a threaded nut 21 across the edge of which is cut a guide groove 22, and this groove receives a guide track or bar 23 which is supported within the casing to extend parallel with the piston rod 20 so that as the rod and threaded nut move longitudinally of the cylinder 17, the nut will be held against turning.

The numeral 24 designates a rotatable control shaft having one end extended through a suitable bearing 25 to the outside of the box where it supports a hand wheel 26. A portion of the shaft from the other end thereof is screw threaded, as indicated at 27, and extends through and is in threaded engagement with the nut 21, extending into the tubular piston rod 20 in the manner shown.

Rotatably supported in and extending through the top wall of the box 16 is a vertical shaft 28 upon the upper end of which is supported a miniature representation 29 of the antenna structure which is mounted upon the mast 7. This miniature antenna constitutes an indicator for designating the position of the main antenna and is coupled with the shaft 22 so as to be rotated simultaneously therewith, by a gear train consisting of the gears 30 and 31 which are mounted respectively upon a wall of the casing and upon the shaft 24, and the gear 32 which is

supported within the casing upon the shaft 28 and is in mesh with the gear 30. In order that necessary adjustments may be made to position the indicator antenna 29 in the proper relation with the mast supported antenna 9 so that these two units may always assume exactly corresponding positions, the gear 32 is coupled with the shaft 28 by a friction coupling in the form of a disk 33 which is carried upon the lower end of the mast 28 and has frictional contact with the adjacent face of the gear 32. A spring 34 may be employed for retaining the gear 32 in firm contact with the friction disk 33.

The cylinder 17 is connected with the fluid passage 5 in the base of the cylinder 3 by a suitable tube or pipe 35 and the cylinder 17, the tube 35 and the part of the cylinder 3 beneath the mast 7 are filled with a suitable fluid 36 by means of which power may be transmitted from the power piston 18 to the piston unit in the cylinder 3.

From the foregoing, it will be readily apparent that in the operation of the present mechanism, when the handwheel 26 is rotated in one direction, the piston 18 will be forced into the cylinder 17 so as to force fluid from the cylinder and through the connecting pipe 35 into the lower part of the cylinder 3, and this will force the mast to move upwardly. Due to the connection between the mast and the cylinder which is maintained by the pins 10 having their points engaging in the spiral grooves 12, the desired rotary motion will be given the mast and the antenna supported thereby. It will also be apparent that the position to which the antenna 30 is moved upon actuation of the piston 18 will be exactly designated by the indicator 29. When the antenna is to be reversely rotated, the hand wheel may be turned so as to shift the piston 18 in the opposite direction in the cylinder 17, whereupon the weight of the mast 7 and the antenna carried thereby will cause the mast to move back down into the cylinder 3, reversely rotating the antenna and forcing the fluid back into the cylinder 17.

While the indicator 29 has been illustrated and described as being in the form of a miniature antenna which is designed to be positioned to extend in the same direction as the antenna 9, it is to be understood that this may be replaced, if desired, by any other suitable form of pointing or indicating means.

What is claimed is:

1. A directional antenna, comprising a vertical mast, an antenna supported horizontally on the upper end thereof, means supporting the same for longitudinal vertical movement, means for imparting rotation in one direction to the mast about its long axis upon upward longitudinal movement and for reversing such rotation on downward movement, means facilitating the application of hydraulic power to the lower end of the mast to effect the raising of the same, and means for applying such hydraulic power from a point remote from the mast.

2. A directional antenna support, comprising a vertically disposed mast upon the upper end of which an antenna is supported, a vertical cylinder into which the lower end of the mast slidably extends, means coupling the mast with the cylinder to effect rotation of the mast in one direction on its long axis with the longitudinal movement of the mast in one direction in the cylinder and for reversely rotating it upon longitudinal movement in the opposite direction,

said cylinder being designed to contain a fluid in its lower end beneath the mast, and means for filling the lower end of the cylinder with fluid under pressure to effect longitudinal movement of the mast upwardly in the cylinder.

5 3. A directional antenna support, comprising a vertically disposed mast upon the upper end of which an antenna is supported, a vertical cylinder into which the lower end of the mast slidably extends, means coupling the mast with the cylinder to effect rotation of the mast in one direction on its long axis with the longitudinal movement of the mast in one direction in the cylinder and for reversely rotating it upon longitudinal movement in the opposite direction, said cylinder being designed to contain a fluid in its lower end beneath the mast, means for filling the lower end of the cylinder with fluid under pressure to effect longitudinal movement 10 of the mast upwardly in the cylinder, said last means comprising a fluid containing cylinder, a piston reciprocable in the cylinder, a fluid pipe line connecting the last-mentioned cylinder with the lower part of the mast cylinder, and means 15 for moving said piston in the last-mentioned cylinder.

20 4. A directional antenna support, comprising a vertically disposed mast upon the upper end of which an antenna is supported, a vertical cylinder into which the lower end of the mast slidably extends, means coupling the mast with the cylinder to effect rotation of the mast in one direction on its long axis with the longitudinal movement of the mast in one direction in the cylinder and for reversely rotating it upon longitudinal movement in the opposite direction, said cylinder being designed to contain a fluid in its lower end beneath the mast, means for filling the lower end of the cylinder with fluid under pressure to effect longitudinal movement 25 of the mast upwardly in the cylinder, said last means comprising a fluid containing cylinder, a piston reciprocable in the cylinder, a fluid pipe line connecting the last-mentioned cylinder with the lower part of the mast cylinder, and means for moving said piston in the last-mentioned cylinder.

30 5. A directional antenna supporting and control means, comprising a vertically disposed cylinder, a mast positioned with one end extending into the upper end of the cylinder and adapted to support a directional antenna upon its other end, a spiral groove of single hand formed in said mast in the portion lying within the cylinder, a guide finger carried by the cylinder and slidably engaging in said groove, the lower end of the cylinder being designed to receive a fluid under pressure for exerting an upward movement of the mast in the cylinder, and means for injecting a fluid into the lower part of the cylinder from a point remote to effect such movement of the mast.

35 6. A directional antenna supporting mechanism, comprising a vertically disposed cylinder, a vertically disposed mast having its lower end slidably extended into the cylinder, means operatively coupling the mast with the cylinder whereby upon longitudinal movement of the mast in one direction it will be given rotational movement about its long axis and reversely rotated upon movement in the opposite direction, a piston 40 within the cylinder at the lower end of the mast,

means providing an anti-friction coupling between the piston and the lower end of the mast whereby the mast may turn independently of the piston, a fluid cylinder, a fluid conducting pipe connecting said fluid cylinder with the lower end of the first cylinder, and means for forcing fluid from the fluid cylinder through said conducting means and into the lower end of the first cylinder.

45 7. A directional antenna supporting mechanism, comprising a vertically disposed cylinder, a vertically disposed mast having its lower end slidably extended into the cylinder, means operatively coupling the mast with the cylinder whereby upon longitudinal movement of the mast in one direction it will be given rotational movement about its long axis and reversely rotated upon movement in the opposite direction, a piston within the cylinder at the lower end of the mast, means providing an anti-friction coupling 50 between the piston and the lower end of the mast whereby the mast may turn independently of the piston, a fluid cylinder, a fluid conducting pipe connecting said fluid cylinder with the lower end of the first cylinder, means for forcing fluid from the fluid cylinder through said conducting means and into the lower end of the first cylinder, said last means including a rotary shaft, a piston in the fluid cylinder and a threaded connection between the rotary shaft and the piston 55 by which reciprocal movement may be given to the last-mentioned piston, and a rotatably supported indicator operatively coupled with said shaft to be turned thereby and coordinated in its rotary movement with the antenna supporting mast whereby the directional position of the antenna will be indicated.

60 8. A directional antenna mechanism, comprising a vertically disposed mast supported for vertical longitudinal movement, an antenna unit supported upon said mast, said mast being supported for rotation about its longitudinal axis, means for imparting rotary movement to the mast in one direction about said axis when the mast is given longitudinal movement in one direction and for reversely rotating the mast when the same is moved longitudinally in the opposite direction, a control unit for the mast including a rotatable shaft, means forming an operative connection between said shaft and the mast whereby upon rotation of the shaft the said longitudinal movement in one direction will be imparted to the mast, an indicator supported for rotation adjacent said control unit and designating the directional position of the antenna, and an operative coupling between said indicator and said shaft whereby the indicator will be moved simultaneously with the turning of the mast and antenna.

65 9. A directional antenna of the character described, comprising a vertically disposed mast supported for vertical longitudinal movement and for rotation on its longitudinal axis, an antenna supported by the mast, fluid pressure means for effecting upward movement of said mast, means for effecting turning of the mast in one direction simultaneously with its longitudinal movement in one direction and for reversing such turning movement upon movement of the mast in the opposite direction, a control 70 unit including a fluid pressure cylinder and a piston movable therein, a fluid conduit connecting said cylinder with said fluid pressure control means whereby upon actuation of said piston in one direction the fluid pressure means will 75

be made operative to raise the mast, rotatably supported screw means connected with said piston for effecting its reciprocation in the cylinder, an indicator supported for rotation on a vertical axis for designating the directional position of the antenna, an operative driving connection between said screw and said shaft whereby the

shaft may be turned simultaneously with the actuation of the mast, said driving connection including a gear supported by the shaft, and a frictional coupling between the gear and shaft facilitating adjustment of the indicator.
